RURAL MAILBOX INDICATOR FLAG

Joseph P. Mancuso, Jamesburg, N. J., assignor of one-fifth to John E. Herche and one-fifth to Earl E. Collins, both of Jamesburg, N. J.

Application June 6, 1955, Serial No. 513,472

3 Claims. (Cl. 232—35)

The present invention relates to a signalling flag which is expressly designed and suitably adapted for use on a side wall of the usual rural free delivery mailbox opposite to the conventionally used flag, that is, the flag which is set up by the resident owner to notify the mail carrier that outgoing mail has been placed in the box for pick-up.

The art to which the invention relates is quite active. Many and varied styles and forms of so-called signalling flags have been offered for use, some for outgoing mail and others for incoming mail and perhaps combinations of the two. The obvious object of the invention here is to provide a novelly constructed and effectually operable flag which is primarily helpful to the resident owner in that it provides positive indication when the mailbox door has been opened, constitutes a visible signal capable of being seen from a distance and thus saving needless trips of the residents of the house to the often empty mailbox.

In the belief that the signalling flag here revealed is an appreciable and practical advance in the art, it will be seen that its adoption and use will, for these reasons, comply with the ordinary manufacturing requirements of manufacturers, will not require the time of the mail carrier to bring the signal into play, and will therefore mutually serve the purposes of all concerned directly or indirectly therewith.

In carrying out a preferred embodiment of the invention, a stop finger, which constitutes a keeper, is affixed on the marginal portion of the usual downwardly swinging cover. A weighted arm is pivoted intermediate its ends on the side wall of the box and provided with a fixed signal or flag, and the flag-equipped end is provided with a freely pivoting latch which also functions as the means for holding as well as tripping the weighted arm and bringing the same into flag displaying position.

Other objects, features and advantages will become more readily apparent from the following description and the accompanying sheet of drawings.

In the drawings, wherein like numerals are employed to designate like parts throughout the views:

Figure 1 is a fragmentary plan view of a box with the automatically actuatable auxiliary signalling flag showing its construction and use;

Figure 2 is a fragmentary side elevational view showing the signalling device in its normal down but ready-to-operate position and also showing, in dotted lines, how it comes into play;

Figure 3 is a section on the vertical line 3—3 of Figure 2 looking in the direction of the arrows;

Figure 4 is a fragmentary perspective view of certain of the details; and

Figure 5 is a fragmentary view showing how the self-pivoting latch trips itself (in full lines) and automatically resets itself (in dotted lines) with the door still closed and, in fact, without having to open the door to accomplish this resetting step.

Referring now to the drawings, the conventional rural free delivery mailbox is denoted as an entity by the numeral 6. It includes the usual bottom and side and end

2

walls. The customary signalling flag indicative of outgoing mail is provided, but is not shown here. It is mounted on the vertical wall opposite that on which the added signal is provided. The latter wall is denoted by the numeral 8 and the conventional hingedly mounted door is denoted by the numeral 10. A so-called bracket is provided at 12, and this may be treated as a sort of a finger having its inner end portion 14 screwed or otherwise fastened on the exterior of the door and projecting beyond the vertical marginal side 16 where it constitutes a keeper as well as an operating element. That is to say, the projecting end portion 18 is the operating element. There is a similar side bracket which is U-shaped, and this is denoted by the numeral 20 and it is fastened to the side wall at the desired place. The aforementioned arm is linearly straight and is denoted by the numeral 22, and it is pivotally mounted intermediate its ends, as at 24, on the bight portion of the bracket. The end portion 26 of the arm is provided with a right angularly disposed fixedly mounted signalling flag 28. This is preferably colored red, but may be of some other color so as not to conflict with the usual red flag. It is also perforated, and the perforations are denoted at 30. From a distance, the over-all appearance or effect of the flag is that of a solid flag. At the same time, it will permit some snow and sleet to pass through the holes and make the device less likely to foul. The longer end portion 32 of the arm is provided with a counterweight 34. The terminal end adjacent the projecting finger 38, that is, the end portion 36, is provided with a substantially triangular member which may be described as a latch 38. This is superimposed on the end portion 36 and is pivoted thereto at 40 so that the corner portion 42 swings up underneath the adjacent overhanging portion of the flag whereby the flag becomes a limiting stop. By using a simple wedge-shaped latch 38, the construction and mode of production and assembling is simplified. The flag, as is clear, serves to prevent the latch from "flipping" backward past dead center and also to prevent the latch from overriding when the latch is in the stop position. When the latch is in the position shown in Figure 2, it will be seen that it underlies the edge of the operating finger 18. Hence, when the mailman opens the door to place mail in the box and the door swings down, it causes the finger to sweep beyond the position of the latch whereupon the weight 32 comes into play and swings the arm and its flag to the erect signalling position shown in the drawings.

Reverting to the operational phases of the disclosure, it will be clear that Figures 1 and 2 illustrate the normal position of the latch-held flag in full lines at which time the flag is down; whereas, the up signalling position is depicted in dotted lines in Figure 2. With reference again to Figure 5, this brings out another feature of the invention in that it clearly reveals the fact that the so-called self-pivoting latch 38 permits resetting of the invention with the door closed, and therefore does not require opening of the door to permit the latch to clear the stop finger 18. So, in Figure 5, it is to be assumed that the flag is being returned in the direction of the arrow A to the resetting position with the latch 38 clearing the stop finger and turning on its pivot 40 and after clearing the stop finger assuming its normal or righted position, as illustrated in dotted lines in this figure.

The foregoing is considered as illustrative only of the principles of the invention. Further, since numerous modifications and changes will readily occur to those skilled in the art, it is not desired to limit the invention to the exact construction and operation shown and described, and accordingly, all suitable modifications and equivalents may be resorted to, falling within the scope of the invention as claimed.

What is claimed as new is as follows:

1. In combination, a mailbox having an open front end and a complementary outwardly and downwardly swingable hingedly mounted closing door for said open end, said box also having at least one vertical side wall, a linearly straight arm pivotally mounted intermediate its ends on and exteriorly of said side wall and provided at its rearward end with a weight, the forward end of said arm being provided with a laterally disposed signaling flag, a latch pivotally mounted on said forward end of the arm and having one end underlying and engaging said flag, the latter serving as an abutment for said latch, and a finger fixed on and projecting beyond the marginal edge portion of said door and releasably engageable with the adjacent end portion of said latch.

2. In combination, a mailbox embodying a vertical side wall and open at its front and having a hinged outwardly and downwardly swinging closing door for said open front, a bracket fixedly mounted on said side wall, an arm pivotally mounted between its ends on said bracket, the rear portion of the arm having a weight, the forward end portion of the arm having a rigid flag attached thereto and extending at right angles therefrom, a latch superimposed on the forward end portion of said arm and having one end underlying and releasably engageable with said flag, and a keeper finger mounted on said door and cooperable with the other end of said latch.

3. In combination, a mailbox embodying a vertical side wall and open at its front and having a hinged outwardly and downwardly swinging closing door for said open front, a bracket fixedly mounted on said side wall, an arm pivotally mounted between its ends on said bracket, the rear portion of the arm having a weight, the forward end portion of the arm having a rigid flag attached thereto and extending at right angles therefrom, a latch superimposed upon the forward end portion of said arm and having its rearward end pivotally mounted on said arm and adapted to underlie said flag with the flag serving as an abutment and limiting stop for the latch, the forward end portion of the latch projecting beyond the forward end of the arm and being beveled downwardly, and a keeper finger mounted on said door and having an end portion adapted to releasably overlie the upper edge portion of said latch.
